UNITED STATES PATENT OFFICE.

JOHN M. MARKS, OF CHICAGO, ILLINOIS.

BUTTON.

SPECIFICATION forming part of Letters Patent No. 712,080, dated October 28, 1902.

Application filed July 18, 1901. Serial No. 68,723. (No model.)

To all whom it may concern:

Be it known that I, JOHN M. MARKS, a citizen of the United States of America, and a resident of Chicago, in the county of Cook and 5 State of Illinois, have invented certain new and useful Improvements in Buttons, of which the following is a specification.

The main object of my invention is to provide an improved form of clasp-button suitable to be employed as a garment-fastener. I accomplish this object by the device shown 10 in the accompanying drawings, in which—

Figure 1 is a vertical section of a stud-button having a socket in its base. Fig. 2 is a 15 vertical section of a similar stud-button having a resilient head adapted to be snapped into the socket of the button shown in Fig. 1 and having immediately below said head an annular shoulder of larger diameter than said 20 head. Fig. 3 is an elevation, partly broken away, showing the two buttons united.

In the form shown my invention is constructed as follows: A tubular shank 1 is spun out to larger diameter at its ends, as 25 shown in Fig. 1, capped at one end with a flanged piece to form a head 2 and at the other end with a piece forming the base 3. In the center of the base 3 is a circular aperture 4, having its edges curled backwardly 30 upon themselves to stiffen the mouth of said aperture. The shank is so formed that the greater diameter than said aperture. A ring space 5 near the aperture 4 is of considerably 35 6 serves to support the mouth of the aperture 4 and adds to its rigidity. A second shank 7 is spun similarly to the shank 1, having the base 8, similar to the base 3, but omitting the aperture, and having mounted at its other end the cap 9. The cap 9 consists of the 40 silent head 10, neck 11 of smaller diameter than said head, and a shoulder 12 of larger diameter than said head. The head 10 is provided with the slots 13 for increasing its 45 resilience and is reinforced by the spiral spring 14. The diameter of the head 10 is slightly larger than that of the mouth 4 of the socket in the base 3 and is adapted by its resilience to snap into said socket.

When used as a cuff-holder, my device is 50 applied as follows: The stud 1 is buttoned into the cuff, the base portion 3 being inward. The stud-button 7 is buttoned into the shirt-

sleeve in the usual manner. The cuff may now be secured to the sleeve by simply snapping the head 10 of the sleeve-button into the 55 socket 4 of the cuff-button. The head 10 will pass in the space 5, and the base 3 will rest firmly on the shoulder 12. It will be seen that the buttons can only be separated by a direct pull along the line of the shanks 1 and 60 7. Relative tilting of the two shanks will be prevented, because the lips of the aperture 4 will be seated about the narrow neck 11 and held there by the resilient head 10, while the base is borne by the shoulders 12. 65

I am aware that the connection of two stud-buttons by a head grasped by a resilient socket is old; but I believe that I am the first to provide means for preventing the relative tilting of the shanks of said buttons, and 70 thereby preventing the accidental separation of said head and socket.

It will be seen that some of the details of my device may be altered without departing from the spirit of my invention. I therefore 75 do not confine myself to such details except as hereinafter limited in the claims.

What I claim as my invention, and desire to secure by Letters Patent, is—

1. The combination of a stud-button comprising a tubular shank having flared ends, a flanged cap on the upper end of said shank, a base carried by the other end of the shank having its ends flanged and bent to embrace the said lower end of the shank, said base 80 having a central circular aperture with the edges of the base formed by said aperture curled backwardly upon themselves, a ring interposed between said base and the lower end of the shank and engaged by said curled 85 edges of the base, and a second stud-button having a tubular shank carrying an imperforate base, and a cap comprising a resilient slotted head extended to form a neck of less diameter than the head, with a spring interposed between the upper end of the head and said neck, the neck being extended to form a shoulder, the ends of the cap being curled inwardly to embrace the upper end of the shank, substantially as described. 90 95

2. The combination of a stud-button formed of a shank, a cap on the upper end of the shank, said cap comprising a head and a shoulder with a contracted neck located be- 100

tween the head and shoulder, a second stud-button comprising a tubular shank the ends of which are flared, a flanged cap carried by the upper end of the shank, a base having 5 its ends bent inwardly to embrace the lower end of the shank, said base having a central aperture therein with the edges of the base formed by the aperture curled backwardly upon themselves, and a ring interposed be-

tween the flared lower end of the shank and 10 the said curled portion of the base, substantially as described.

Signed at Chicago this 16th day of July, 1901.

JOHN M. MARKS.
